United States Patent

Des. 235,785
Patented July 8, 1975

235,785

MICROBIOLOGICAL NUTRIENT MEDIUM HOLDER

Kenneth Dale Collister, Elkhart, Ind., and Leighton Clifford Johnson, Edwardsburg, Mich., assignors to Miles Laboratories, Inc., Elkhart, Ind.

Filed July 5, 1974, Ser. No. 486,012

Term of patent 14 years

Int. Cl. D24—02

U.S. Cl. D32—1 A

FIG. 1

FIG. 2

FIG. 3

FIG. 1 is a perspective view of a microbiological nutrient medium holder embodying the new design;

FIG. 2 is a top plan view thereof; and

FIG. 3 is a cross-sectional view of the holder depicted in FIG. 1 taken along the line 3—3 of FIG. 1.

We claim:

The ornamental design for a microbiological nutrient medium holder, substantially as shown and described.
